UNITED STATES PATENT OFFICE.

FRANK JOHN SCHOLL, OF LONDON, ENGLAND.

FOOT ARCH SUPPORT.

Application filed December 31, 1926, Serial No. 158,327, and in Great Britain December 5, 1925.

This invention relates to foot arch supports and more particularly to those of the type wherein the underside is so hollowed that at some part or parts, a relatively narrow edge is presented to the inner sole of foot coverings with which the supports are used. It aims to provide improved means for covering such narrow edge or edges so as to prevent or very materially reduce chafing and wear of the inner sole of footwear to which the arch supports are applied.

In connection with devices of this kind embodying a metal supporting plate, it has been proposed to protect the inner sole which is usually of leather, against damage due to edge pressure and friction of the supporting plate, by employing a metal plate for the said edge to bear upon, such plate being either separate from or fixed to the metal supporting plate or its cover. Metal protectors add unduly to the weight of the foot covering and the object of the present invention is to effect certain improvements, applicable in general to foot arch supports of the kind referred to, according to which the protection is afforded by material other than metal, but which is yet of a character unlike or different from that of the inner sole, and hence should not be confused with the leather protectors, either fixed or detachable, which have hitherto been proposed for this purpose.

Numerous proposals have been made for encasing metal foot supporting plates wholly in textile material and also for coating one or both sides of a metal foot support with celluloid. Where both sides of the metal plate are to be so coated, it has been proposed also to use a perforated plate, whereby the covering material can extend through the plate.

The present invention is differentiated from known devices such as referred to above, in that it is concerned only with the provision of a covering or protector for those edges of an arched foot support which otherwise would bear directly on the inner sole of the foot wear and provides for the concentration of protecting means at parts where undue wear would otherwise occur without at the same time adding unnecessary weight to the device.

A protector according to the invention may be composed of a layer or layers of hard-wearing woven fabric, horn, ebonite, celluloid or allied composition produced by

chemical agency (most of which substances are known per se in the manufacture of foot arch supports), or of any appropriate combination of such materials, providing a durable bearing surface or cushioning edge for the support within a shoe which will not easily deteriorate under moisture from the foot nor chafe away to expose a sharp-wearing edge of the metallic or hard material body portion of the support with injurious effect upon the inner sole of the footwear, the protector being given the form of a pad which may be secured to the support in any suitable way, either permanently or in a removable manner, it being understood that such protector pad is incorporated in the arched supporting member always in association with the edge or edges which is or are wearably presented to the boot or shoe. The arched supporting member proper may be of metal as above suggested, or any other sufficiently stiff material or combination thereof, it being recognized that wear of the inner sole of a boot or shoe, due to localized pressure as aforesaid is not dependent solely upon the hardness of the arched supporting member, but may be just as apparent where there is greater movement of a less hard arched supporting member, the wear upon the inner sole of a shoe in all cases being influenced by the rubbing or relative movement that occurs.

In the constructional forms of foot arch supports according to the present invention, no two surfaces of material in contact are identical and hence, materials of differing coefficients of friction can be chosen to produce the best results for any particular requirement.

The protector pad may be attached to the customary cover of a metal supporting plate, or it may be attached to, or form part of a pocket-like or sleeve-like member adapted to be slipped over the metal supporting plate so that a part lies between it and the cover, if employed. Further, the metal supporting plate may be cut or shaped so as to constitute a reinforcement for protecting material applied thereto in appropriate way as by moulding, so that a relatively broad surface instead of a narrow edge is presented to the inner sole.

The feature of making the protecting pad from a hard-wearing material such as specified, is that such material is not subject to deterioration from moisture nor readily

chafed away under friction from the metallic body of the support or the leather portion of the inner sole. Moreover, such material provides a more durable structure 5 wherein the material forming a protective pad and cushioning agent may be made thinner than would be possible with the use of leather for the same purpose. It is well known that leather quickly deteriorates and 10 wears away under moisture and friction from the foot, especially if the leather is employed against metal or any other stiff and sharp-edged material.

In the drawings, Fig. 1 illustrates in a 15 fragmentary perspective view a foot arch support comprising a metal plate with pad or cover applied and Fig. 2 is a perspective view of a removable pocket-like form of pad or cover adapted to be applied to the fore 20 end of a foot arch support plate.

In Fig. 1, a protector cap 1 embodying the 25 invention is shown applied to the usual metal plate 2 of an arch support having a leather cover 3. Said cap is made of celluloid, horn or other material such as above described and is overlappingly applied permanently or otherwise to the plate 2 and cover 3 after assembly, it being assumed that 30 whereas there is a layer upon which the plate 2 bears, a layer also extends over the other side of the cover 3 whereon the foot rests. If desired, the protective medium or cap may envelop merely the fore end of the metal plate 2 and need not be extended to include the cover 3, as will be obvious.

Fig. 2 illustrates a simple and preferred 35 form of protector 1 comprising two layers

which may each be of the same material or one of one material and the other of a different material attached together marginally in 40 any suitable manner such as by stitching. Obviously also, such a protector (which is applied to the fore end of the plate simply by slipping the same thereover so that one layer occupies a position between the plate 45 and cover) may be made by incising a single piece of material of appropriate thickness for the desired two layers, and no marginal uniting of the pieces would then be necessary.

The word "celluloid" as used in the following claim is intended to include as equivalents, the hard-wearing materials of woven-fabric, horn, ebonite or similar materials suitable for the purposes of the invention, and for such reason it is not intended that the invention shall be limited by the claim to the use of celluloid alone.

Having now particularly described and ascertained the nature of my said invention and in what manner the same is to be performed, I declare that what I claim is:—

A foot arch-support embodying in combination with a metal arch supporting plate, a protective pad placed on the end of said plate along the edge where the latter would otherwise bear directly upon the inner sole of the footwear, said pad being composed of thin layers of celluloid united along the marginal edge of the plate to cover the latter.

Signed at London, England, this 15th day of Dec., 1926.

FRANK JOHN SCHOLL.
